UNITED STATES PATENT OFFICE.

EMIL BUEHRER, OF GREEN BAY, WISCONSIN, ASSIGNOR TO THE GEO. KRESS CO., OF GREEN BAY, WISCONSIN, A CORPORATION OF WISCONSIN.

HUMIDIFIER FOR HEATING UNITS.

Application filed June 9, 1926. Serial No. 114,664.

This invention relates to a humidifier. It is particularly directed to a humidifier for use with furnaces, latrobes, stoves, or other heating appliances of this type which are applied in dwellings and other buildings.

An object of this invention is to provide a humidifier in which the water pan or container is adapted to be placed inside the drum of a hot air furnace or stove, and in which the proper amount of water is maintained in this pan without requiring an auxiliary compartment outside of the furnace.

A further object is to provide a humidifier in which the manipulating valve and also the automatic control valve are located wholly exteriorly of the furnace, so that heat from the furnace does not make the valve rapidly deteriorate but, instead, permits a continuous and prolonged use of the valve without renewal.

A further object is to provide a novel form of humidifier in which the utmost freedom of access to the valve is afforded, so it may be renewed, adjusted or replaced without opening any portion of the furnace.

A further object is to provide a humidifier in which the water level may be maintained at any desired height, and in which its height may be regulated from the outside of the furnace by properly adjusting the valve, and to provide a humidifier in which the support for the float is above the water level, so that it is kept free from sediment and deterioration, usually present in these devices, and thus secure a long life for the apparatus.

A further object is to provide a novel form of humidifier in which a very low level for the water may be easily maintained without any possible chance of overflow from the pan upon the hot parts of the furnace, and to provide an overflow in the valve exteriorly of the furnace so that in case the valve should fail to function, no damage can result.

An embodiment of the invention is shown in the accompanying drawings in which:—

Figure 1 is a fragmentary view of the upper portion of a furnace with parts broken away and parts shown in section.

Figure 2 is a sectional view showing a plan of the hot water pan and valve mechanism.

Figure 3 is an enlarged vertical sectional view partly broken away, showing the construction of valve and associated parts.

Referring to the drawings, it will be seen

that a conventional type for hot air furnace has been illustrated, as composed of a heating unit 1, and an outer shell 2, which extends upwardly and forms the top of the furnace.

The water pan 3 is seated upon the top of the heating unit of the furnace and may have an irregular outline, as indicated in Figure 2, to secure the requisite conducting surfaces. This water pan is provided with an end piece 4, as shown most clearly in Figure 3, which is equipped with a fitting 5 provided with a stem guide 6. An outwardly extending pipe 7 is screwed into the fitting 5, as indicated, and projects through the removable plate 8, which forms a continuation of the shell 2 of the furnace, such pipe being attached to the plate, as indicated in Figure 3. This plate may be provided with clamps 9, to permit its ready detachment from the shell of the furnace and also to secure the utmost rigidity when it is in place.

The pipe 7 extends through the plate 8 and its threaded outer end is received by a fitting 10, which is also provided with a stem guide 11. This fitting screws into the body portion of the valve 12, such valve being supplied with water by means of the supply pipe 13, a manually controlled cut off valve 14 being interposed between the pipe 13 and the valve 12. The valve body is provided with a main recess or chamber 15 into which the pipe 7 opens. This chamber is internally threaded at its inner end and receives the spanner nut 16 which, in turn, clamps a rubber or other yielding gasket 17 in place. This gasket and the nut 16 form in effect a valve seat centrally apertured. A tapered valve 18 cooperates with this seat and is formed integrally with a threaded stem 19. The stem 19 is adjustably screwed into an enlargement 20 formed on the inner end of the float controlled rod or valve rod 21. In effect, therefore, the rods 19 and 21 form an adjustable valve rod.

The outer end of the rod 21 is provided with an enlarged externally threaded member 22 which is joined by means of a coupling 23 to a similarly threaded member 24. The member 24 is slotted and receives the short arm 25 of the float lever. This float lever comprises a rod 26 at the outer end of which a float 27 is carried. The float lever is pivotally supported by means

of an overhanging bracket 28 securely bolted to the end piece 4 in the wall, as most clearly shown in Figure 3.

The body portion of the valve 12 is provided with a removable plug 29 to permit inspection or adjustment of the parts of the valve. Thus the plug may be removed and the stem 19 rotated or adjusted by a suitable instrument to regulate the point or height 10 at which the float will cut off the water supply. Further, it is to be noted from Figure 3 that an overflow opening 30 at a point higher than the pipe 7 is provided in the valve chamber 15, and such overflow opening 15 communicates with the overflow pipe 31, as indicated in Figures 1 and 2.

In operation, the valve is preferably adjusted so that the float will maintain a low water level and thus avoid all possibility 20 of overflow from the water pan. If, however, through any wear or defect in the valve, water should continue to pass the valve, it will overflow through the pipe 31, exteriorly of the furnace, and thus prevent 25 water from falling upon the hot parts of the furnace.

It is to be noted particularly that the valve may be renewed, replaced, or adjusted without opening the furnace chamber, as it 30 is entirely exterior to such chamber. Further, it is to be noted that the float is supported above the water level and, consequently, no damage to its supports can occur 35 from the accumulation of sediment which is an ever present detriment to the usual type of floats.

It will be seen further, that the entire device may be lifted out of the furnace, if desired, by detaching the clamps 9, and removing 40 the plate 8, together with the parts secured thereto.

Although the invention has been described in considerable detail, such description is intended as illustrative rather than limiting as 45 the invention may be variously embodied and as the scope of such invention is to be determined as claimed.

I claim:

1. A humidifier for furnaces having a heating element and an outer shell, said

humidifier comprising a water pan adapted to rest upon the heating element, a supply pipe adapted to pass through the outer shell and opening into the water pan, a float and float operated lever positioned within the water pan, a rod extending from said float lever through said supply pipe, a valve carried by said supply pipe and adapted to be located externally of said shell, said valve having a body portion and a movable member, said movable member being operated by said rod and said body portion having an overflow pipe mounted at a point higher than said pipe.

2. A humidifier for a furnace having a heating element and an outer shell, said humidifier comprising a water pan adapted to rest upon said heating element, a supply pipe having a supply valve, said supply valve being adapted for positioning externally of said shell, said supply pipe leading from said valve through a wall of said water pan, a float and float operated lever positioned in said pan, a rod connected to the float lever and passing through said pipe into the body portion of said valve, said valve having a movable element controlled by said rod and adjustable externally of the said furnace, said body portion having an overflow opening located at a point higher than 80 said pipe, and below the top of said pan.

3. A humidifier for a furnace comprising a water pan, a horizontally extending pipe leading through one wall of said water pan and outwardly therefrom, all portions of 85 such pipe being located below the top of said pan, a rod passing through said pipe, a valve carried by the outer end of said pipe and having a movable portion connected to 90 said rod, said valve having an overflow port located at a point below the top of the water

pan, a lever pivotally mounted within said pan and operatively connected to said rod, a float within said pan and having a rod 95 connected to said lever.

In testimony that I claim the foregoing I have hereunto set my hand at Green Bay in the county of Brown and State of Wisconsin.

EMIL BUEHRER.
